UNITED STATES PATENT OFFICE.

JACOB WILLIAM WAGNER, OF GARRETT, AND HENRY SHENK, OF CEDAR, INDIANA.

BOW-FACING OAR.

No. 825,780.

Specification of Letters Patent.

Patented July 10, 1906.

Application filed December 11, 1905. Serial No. 291,283.

To all whom it may concern:

Be it known that we, JACOB WILLIAM WAGNER, residing at Garrett, and HENRY SHENK, residing at Cedar, in the county of Dekalb, in the State of Indiana, citizens of the United States, have invented certain new and useful Improvements in Bow-Facing Oars; and we do hereby declare that the following is a full, clear, and exact description of the invention, which will enable others skilled in the art to which it appertains to make and use the same, reference being had to the accompanying drawings, which form part of this specification.

15 Our invention relates to improvements in bow-facing oars.

The object of our present invention is to provide a cheap, simple, efficient, and convenient bow-facing oar mounted on a pivotal supporting-plate provided with two fulcrums to materially increase the leverage and enable the operator to face the bow of the boat, a novel means of mounting the supporting-plate, and a novel self-locking pin for securing the plate in position.

25 Our invention consists of an upright supporting-bracket rigidly fixed to either the inner or outer face of the gunwale of the boat on which it is employed, a swinging plate horizontally mounted on the bracket by a detachable connection of novel construction, and a two-part oar mounted on the said plate and provided with two separate and independent fulcrums.

35 The principal novel features of our invention reside in the two-fulcrum construction and arrangement of the oar and the means for detachably mounting the same.

Similar reference-numerals indicate like parts throughout the several views, in which—

45 Figure 1 is a perspective view of our invention in position on the side or gunwale of the boat, broken away and showing the relation of the operative parts. Fig. 2 is a detail of the pivoted sleeve by which the forward section of the oar is guided, the sleeve being shown in vertical section. Fig. 3 is a side view of the oar-supporting bracket in position on the side of the boat.

50 The upright supporting-bracket 1, of any proper size and contour, is rigidly secured to either the inner or outer face of the side or gunwale 8 of the boat, as shown in Fig. 3, in

any proper manner, as by screws 2, and is 55 provided at its ends with the upright lugs 3, having their upper end provided with open-topped sockets 4. This bracket is also provided at its central portion with a pair of upright laterally-apertured lugs 5, adapted 60 to receive the pin 6, having a head on one end and its other end provided with centrally-pivoted section 7, adapted to retain a vertical position in use by gravity, as shown in Fig. 3, thereby securing the pin in position. 65

On the bracket 1 is pivotally mounted the oar-supporting plate 9, Fig. 1, whose inner end is provided with the extended bifurcated lugs 10, provided with a fixed pin 11, adapted to form a bearing in the respective sockets 4 70 of the bracket-lugs 3. This plate is also provided at its inner end, midway of the lugs 10, with a laterally-apertured lug 12, adapted to be loosely mounted between the said lugs 5 and to be pivotally secured thereto by means 75 of the said removable pin 6. In a suitable aperture in the lug 12 is fixed a vertically-arranged pin or bolt 13, on which is pivotally mounted the handle-section 14 of the two-part oar. This section 14 has its outer end 80 bifurcated and adapted to loosely receive the reduced inner end of the paddle or other section 15 of the oar. This oar-section 15 is loosely or slidably mounted at or near its inner end in an upright guide stirrup or sleeve 85 16, which is pivotally mounted in the extended outer end of the plate 9 in any suitable manner, preferably by means of a pendant screw 17, on which are preferably arranged a pair of washers 18, one on each side 90 of the plate 9, the whole being secured in position by means of a nut 19 on the screw-threaded outer end of the screw 17, Fig. 2. This guide 16 forms a pivotal fulcrum for the blade-section. 95

The operation of our invention thus described is obvious and, briefly stated, is as follows: Referring to Fig. 1, either end of the gunwale 8 may be considered as pointing toward the bow of the boat, though for convenience of description it is assumed that the gunwale 8, which is shown, is upon the left side of the boat, and the operator faces the bow or in the direction of the arrow, thereby operating the oar shown with his left hand and its exact duplicate (not shown) with his right hand. When it is desired to propel the boat forward, the operator seizes the handle-

sections of the oars and first pushes them forward on their fulcrum 13 in the usual manner, thereby correspondingly swinging the inner end of the blade-section 15 rearwardly on its pivotal fulcrum 16, whereby the blade 20 will be swung correspondingly forward into position for the stroke or effective movement thereof, after which the operator pulls on the oars simultaneously, thereby bringing the oar-blades rearwardly in their effective movement. In the forward or return movement of the oars the operator bears down on the handle-sections of the oars sufficiently to properly tilt the outer end of the plate 9 upwardly, thereby enabling the blade-sections of the oars to clear the surface of the water during this movement. It is obvious that by this construction the operator, who faces the bow of the boat, can propel the boat forward instead of backward and that the relative position of the pivoted fulcrums for the blade-section can be variously placed to suit the operator. To remove the oars, with their supporting-plate, it is only necessary to swing the pivoted section 7 of the pin 6 into its longitudinal position and then remove the pin, after which the plate 9, with its surmounted oar, can be readily lifted out of its bearings at pleasure. This plate 9 can obviously be replaced in position with equal convenience and secured therein by inserting the pin 6 again in place.

It is apparent that our novel form of pin 6 avoids the use of either a key or a nut and is more convenient and secure than either of them.

Our invention thus described is simple, convenient, and very efficient and has but small liability of getting out of repair.

What we desire to secure by Letters Patent is—

1. In a bow-facing oar the combination of an upright bracket provided at its ends with open socket-bearings and at its central portion with laterally-apertured lugs; a horizontal plate pivotally mounted in the bearings and lugs of said bracket, and provided upon its outer free end with a pivoted stirrup or guide; and a two-part oar whose handle-section is fulcrumed near the inner edge of the said plate, and whose blade-section is slidably mounted in the said guide and is pivotally connected at its inner end to the said handle-section, all substantially as described. 45

2. The combination in a bow-facing oar of an upright bracket having open socket-bearings at its ends, and provided with laterally-apertured lugs at its central portion; a horizontal plate resting in the socket-bearings, and having an apertured lug which extends 60 between the before-mentioned lugs, and a removable bolt extending through all of said lugs; and a two-part oar connected with the horizontal plate and supported thereby, whose handle-section is fulcrumed near the 65 inner edge of the said plate, and whose blade-section is slidably mounted in the said guide, and is pivotally connected at its inner end to the said handle-section, all substantially as described. 70

Signed by us at Fort Wayne, Allen county, State of Indiana, this 8th day of December, A. D. 1905.

J. WILLIAM WAGNER.
HENRY SHENK.
